CONTAINER FOR IMPLANTATION TABLETS

Erich Putter, Maplewood, N. J., assignor to
Schering Corporation, Bloomfield, N. J., a corporation of New Jersey

Application October 17, 1941, Serial No. 415,346

6 Claims. (Cl. 206—63.2)

This invention relates to an improved container for medicinal tablets of the type known as implantation tablets which are inserted into the body of a patient by means of what is known as a trocar needle. Implantation tablets are usually packed for use by embedding them in cotton in a container which necessitates that a physician utilize sterilized tweezers not only to transfer the tablet from the container to the needle but to remove also the cotton in which it was wrapped for protection. This is a tedious and difficult procedure and if the physician is at all careless the tablet is apt to be contaminated. Furthermore, tablets of this nature readily crumble and disintegrate so that if they are not handled carefully in their transfer to the needle, they are apt to become broken or reduced in size and as such tablets are made in exact dosages this may prove serious and dangerous.

The purpose of the present invention is to provide an improved container which will enable the ready transfer of the implantation tablet contained therein to the physician's needle without any danger of contaminating the tablet or damaging it.

Other objects as well as the advantages and construction of this novel container will become apparent after a perusal of the following description, read in connection with the accompanying drawing, in which Fig. 1 is a perspective view of the container illustrating the manner in which the tablet is packed therein; Fig. 2 is an exploded, perspective view showing the parts of the container in disassembled condition; Fig. 3 is a perspective view illustrating one manner in which the trocar needle may be loaded from the container; Fig. 4 is a perspective view illustrating the next step in loading the trocar needle and Fig. 5 is a perspective view of a modified form of the container.

Before taking up the description of the container, it is deemed advisable to consider briefly the construction of the type of trocar needle which is usually utilized in inserting an implantation tablet into the body of the patient. As is shown in Figs. 3 and 4 of the drawing, the trocar needle is composed of an elongated metal tube which is divided into a needle end A and a loading end B by means of a knurled collar C which serves as a finger piece. The loading end B of the needle is cut away at its outer extremity to provide a trough-like portion D upon which is placed the implantation tablet E to be passed through the needle and into the body of the patient.

In accordance with this invention, the tablet E is packed for sale in a sterilized elongated glass tube F which has an inside diameter only slightly greater than the outside diameter of the loading end B of the needle so that while the latter may be readily inserted therein, there is prevented any unnecessary play between such parts while the loading end B of the needle is inserted in the tube F and during the transference of the tablet E from the container. The glass tube F is enlarged at its ends to provide two mouths G, G adapted to receive stoppers H, H, the outer ends of such mouths being preferably provided with beads I, I. Each of the stoppers H is provided with a glass rod J and, when made of rubber, preferably with an integral substantially cylindrically shaped sealing cap K which prior to the sealing of the stopper in place on the tube F or during the removal of such stopper extends outwardly from the stopper H, as is shown in Fig. 2 of the drawing, while when the stopper is in place on the end of the tube F, such cap K extends over the mouth G of the tube, as is shown in Fig. 1 of the drawing, to provide an effective seal against extraneous matter entering into the tube and contaminating the tablet E. A bead is provided on the outer end of the cap K to lock the latter in position on the container until positively removed therefrom.

The two glass rods J, J, have an external diameter only slightly less than the inside diameter of the container or tube F so that they fit fairly snugly within the tube and yet can be readily removed therefrom. The length of the two glass rods J, J is such that their ends just engage the ends of the tablet E. Thus the two glass rods form between them a relatively closed chamber, whose end walls gently press upon the ends of the tablet E (see Fig. 1) to prevent it from moving materially in the container and to protect it against destruction or damage during handling. This gentle pressing effect is enhanced by the cushioning contact of the rods J, J with the walls of the container through the rubber stoppers H, H. It will also be observed from the drawing (note Figs. 1 and 3) that the length of each rod J plus the length of the tablet E is approximately equal to the length of the loading end B of the trocar needle. In other words, the length of the tube or container F is equal to approximately twice the length of the loading end B of the trocar needle minus the length of the tablet E. Thus when the loading end B of the needle is inserted into the container with the collar C thereof in engagement with the beaded end I of the container the outer extremity D of such needle end

will almost be in contact with the end of the opposing glass rod J. This is readily observable in Fig. 3 of the drawing. By providing the container or tube F with a length from one end thereof to the outer end of the opposing rod J at least equal to the length of the loading end B of the needle so that the latter may be wholly inserted into the container in the manner described, there is little likelihood of a mishap in the transfer of the tablet or the contamination thereof.

It will be evident from the foregoing, that when the end B of the needle is inserted into the container in the manner explained, the tablet E will become positioned on the U-shaped or trough-like extremity D of such end of the needle. The tablet therefore can be readily removed from the container and forced further into the needle to ready it for application to the patient by means of a sterilized push rod L, as is shown in Fig. 4 of the drawing. As an alternative, the other stopper H and glass rod J attached thereto can also be removed and the push rod L which is slightly smaller in diameter than the bore of the tube F, inserted into the open end of such tube to push the tablet E home within the needle. It will thus be seen that the loading of the needle is made quite simple and there is removed any danger of the tablet E becoming contaminated during the loading of the needle.

Instead of providing two stoppers and glass rods for the container, the container may have a closed end as is illustrated in Fig. 5 of the drawing, the closed end in this embodiment taking the place of the end of one of the glass rods J and being spaced from the mouth of the container F a distance approximately equal to the length of the loading end B of the trocar needle. In all other respects the parts shown in Fig. 5 are similar to the corresponding parts shown in the container illustrated in Figs. 1 and 2.

I claim:

1. A container for a medicinal tablet comprising an elongated glass tube, open at both ends and formed at such ends to receive closure members, said container being continuous throughout its length and having an interior diameter such as to prevent material transverse movement of the tablet to be contained therein, closure members for said container ends, glass rods connected to said closure members and extending therefrom to points within the tube, the lengths of said rods being such that when said closure members are in position on said glass tube, the free ends of said rods will just engage the ends of a tablet deposited therein and will confine such tablet against longitudinal movement in the container.

2. A container such as defined in claim 1, in which the interior diameter of said tube is only slightly greater than the diameter of said glass rods so that in the region of said tube intermediate the ends of said glass rods there is provided a substantially closed chamber for the tablet.

3. A container such as defined in claim 1, in which said closure members are made of rubber and are provided with cylindrically shaped capping portions adapted to overlie the portions of the tube surrounding the body portions of said members and to maintain the ends of the glass rods in cushioned engagement with the ends of the tablet.

4. A container for a medicinal tablet comprising an elongated body having a tablet containing portion whose interior cross-sectional area is such as to prevent material transverse movement

of the tablet to be carried therein and having a stop against which one end of such tablet is to abut, a stopper for said container including a closure coacting with the latter to effectively seal the opening for such stopper against the entry of contaminating material and a retaining rod extending into the body of the container, the length of said retaining rod being less than the length of said container body and being such that when the stopper is in position on the container, the free end thereof can just engage the other end of the tablet adjacent to said stop, and stop means provided on said stopper and coacting with said container body to limit the insertion of said retaining rod therein and to position the latter so that when said closure effectively seals the opening for such stopper, the free end of said rod will be in position to cooperate with said stop to positively confine the tablet against material longitudinal movement in the container.

5. A container for a medicinal tablet comprising an elongated tubular body open at both ends and formed at such ends to receive stoppers, said tubular body having intermediate its ends a tablet containing portion whose interior diameter is such as to prevent material transverse movement of the tablet to be carried therein, a stopper for each end of said container each including a closure coacting with said container body to effectively seal the opening for such stopper against the entry of contaminating material and a retaining rod extending into the body of the container, the combined lengths of said retaining rods being less than the length of said container body and being such that when both stoppers are in position on the container, the free ends thereof can just engage the ends of a tablet carried in such container, and stop means provided on said stoppers and coacting with the ends of said container body to limit the insertion of said retaining rods therein and to position the latter so that when said closures effectively seal the openings for such stoppers, the free ends of said rods will be in position to positively confine the tablet against material longitudinal movement in the container.

6. A container for a medicinal tablet comprising an elongated body closed at one end and open at the other end to receive a stopper, said elongated body being continuous throughout its length and having an interior cross-sectional area such as to prevent material transverse movement of the tablet to be carried therein, a stopper for said container including a closure coacting with the latter to effectively seal the opening for such stopper against the entry of contaminating material and a retaining rod extending into the body of the container, the length of said retaining rod being less than the length of said container body and being such that when the stopper is in position on the container, the free end thereof can just engage a tablet positioned against the closed end of such container body, and stop means provided on said stopper and coacting with the open end of said container body to limit the insertion of said retaining rod therein and to position the latter so that when said closure effectively seals the opening for such stopper, the free end of said rod will be in position to cooperate with the closed end of said container body to positively confine the tablet against material longitudinal movement in the container.
